US0D1007148S

(12) United States Design Patent (10) Patent No.: US D1,007,148 S
(45) Date of Patent: * Dec. 12, 2023

(54) LUGGAGE

(71) Applicant: A11PHA ApS, Rødovre (DK)

(72) Inventors: Sebastian Cann-Svärd, Rødovre (DK);
Thomas Morén, Rødovre (DK)

(73) Assignee: A11PHA APS, Rødovre (DK)

() Term: 15 Years

(21) Appl. No.: 35/515,515

(22) Filed: Mar. 25, 2022

(80) Hague Agreement Data

Int. Filing Date: Mar. 25, 2022

Int. Reg. No.: DM/220607

Int. Reg. Date: Mar. 25, 2022

Int. Reg. Pub. Date: Nov. 4, 2022

(51) LOC (14) Cl. 03-01

(52) U.S. Cl.

USPC D3/271.4; D3/279

(58) Field of Classification Search

USPC ... D3/271.1, 271.4, 273, 276, 279, 289, 902

CPC A45C 5/03; A45C 2005/037; A45C 2005/035

See application file for complete search history.
